UNITED STATES PATENT OFFICE.

NATHAN M. LOWER, OF SCHENECTADY, NEW YORK, ASSIGNOR TO LOCOMOTIVE STOKER COMPANY, OF SCHENECTADY, NEW YORK, A CORPORATION OF PENNSYLVANIA.

ENGINE-GOVERNOR.

1,305,387.

Specification of Letters Patent. Patented June 3, 1919.

Application filed February 6, 1914. Serial No. 816,925.

To all whom it may concern:

Be it known that I, NATHAN M. LOWER, a citizen of the United States, and resident of Schenectady, county of Schenectady, and 5 State of New York, have invented certain new and useful Improvements in Engine-Governors, of which the following is a specification, and which are illustrated in the accompanying drawings, forming a part 10 thereof.

The invention relates to governors adapted to vary the travel of the engine valve due to the centrifugal action of one or more weights mounted upon the crank shaft, and 15 controlling a shiftable eccentric, to the strap of which the valve stem is attached.

The object of the invention is to provide 20 means for increasing the efficiency of such devices, and for changing the action of the governing weight or weights upon the eccentric 25 to effect the governing action at varying speeds.

In governors of this type it has been the 30 practice to employ springs of suitable tension to counteract the centrifugal action, according to the speed desired. In order to provide for a change of speed it has been necessary to substitute springs of different tension; the governor, when in service, being 35 adapted only to insure a single or uniform engine speed. The present invention provides means for augmenting the increase of the spring tension at different speeds at the same ratio as the effective centrifugal force 40 upon the weights increases as they move outward; and it also provides means for varying the spring tension to vary the speed at which the governor will act, the augmentation 45 of the spring tension as the weights move out being correspondingly varied. It further provides means for effecting this variation in spring tension and action while the engine is running.

The accompanying drawings represent one 50 embodiment of the invention, though its scope is sufficient to include any means for effecting the result as stated. In the drawings—

Figure 1 is a detail longitudinal sectional 55 view of a governor on the line of the engine crank shaft, some parts being shown in elevation;

Fig. 2 is a detail sectional view on the

line 2—2 of Fig. 1, and showing some parts of the device in elevation;

55

Fig. 3 is a detail sectional view on the line 3—3 of Fig. 1, some of the parts being represented in elevation, the governor weights being in retracted position;

Fig. 4 is a detail sectional view on the line 60 4—4 of Fig. 1, the governor weights being in their outer position;

Fig. 5 is a view similar to Fig. 3, the weights being shown in their outer position;

Fig. 6 is a detail of the lever for varying 65 the spring tension;

Fig. 7 is a sectional detail on the line 7—7 of Fig. 1;

Figs. 8 and 9 are diagrammatic views 70 showing the eccentric, and parts associated therewith, in different positions.

The crank shaft of the engine in connection with which the governor is used is represented at 10, the wrist-pin of the crank being shown at 11. This crank and the governor mechanism are inclosed within a casting 12 of suitable form. The valve rod or stem is shown at 13, and as being connected to a nipple 14 formed on the strap 15 encircling an eccentric 16. The eccentric is 80 pivotally mounted upon a post 17, set in a disk 18, which is fixed upon the shaft 10.

The usual governing weights, shown as two in number, are employed and are designated 19, 20, being pivoted, respectively, 85 upon the posts 21, 22, set in the disk 18, and are connected together by means of a link 23. As shown, the usual retracting springs 24, 25, are associated with the weights 19, 20, being anchored to the disk 18, respectively, 90 at 26, 27. The governing weights are connected to the eccentric 16 by means of a link 28 attached to one of them, as 19, at the point 29.

As thus far described the governor is without novel features. In the absence of other elements the outward movement of the governing weights, due to centrifugal force in excess of the tension of the springs 24, 25, swings the eccentric 16 about its pivot 17 so 100 as to cause its center to approach the center of the shaft 10, thereby decreasing the throw of the valve and reducing the supply of steam to the engine in the usual manner tending to maintain a uniform speed. In 105 order to augment the spring tension to corre-

spond at different speeds with the augmentation of the effective centrifugal force as the weights move out and thereby prevent the action known as pounding, and to vary the speed at which the governor will act without changing the springs and without stopping the engine, additional mechanism is provided.

This is accomplished, in the construction illustrated, by introducing an additional spring attached at one end to the eccentric and at the other to the free end of a lever which is swung backward by the shifting of the eccentric responsive to the outward movement of the weights; and there is also provided a manually shiftable fulcrum for the lever, whereby not only the tension of the supplemental spring may be varied but its elongation, due to the movement of the weights, may be varied to correspond with the centrifugal force of the weights.

Such lever 30 is pivotally attached at one end, 31, to the eccentric 16, and at the other end to the supplemental spring 32, anchored at 33 at the farther side of the eccentric, although not necessarily diametrically opposite the point 31, it being important only that the points of attachment of the lever and of the spring to the eccentric be upon opposite sides of the radius upon which the eccentric is pivoted. The fulcrum for the lever preferably takes the form of an anti-friction roller 34, carried by a sleeve 35 rotatably and slidably mounted upon the shaft 10. Movement of the eccentric from the position of Fig. 2, the weights being retracted, toward the position assumed as shown in Fig. 4 when the weights are at their outer position, stretches the spring 32 by moving apart the points of attachment of its ends, the eccentric being carried to the right and the free end of the lever to the left. The spring 32, therefore, not only supplements the springs 24, 25, but the increase of its pull is rapidly augmented by the lever action, the spring being stretched from both ends.

The lever 30 is provided with an oblique channel 36 across its inner face for engagement by the roller 34, which is so positioned that its axis is oblique to the engine shaft. The shifting of the fulcrum along the channel has the effect of swinging the lever on its pivot, thereby changing the tension of the spring 32; and this action is augmented by varying the depth of the channel from end to end, its greatest depth being at the end most remote from the pivot 31. The sleeve 35 is shiftable longitudinally by means of a hand lever 37, mounted upon a shaft 38 extending through the casing 12, and carrying a yoke 39,—a pair of links 40 connecting the yoke arms with studs 41 formed upon a shifting annulus 42 associated with the sleeve.

The details of the sliding sleeve construction, as shown, are as follows:—The sleeve 35 bears directly upon the shaft 10 at its forward end, as shown at 43. At its rearward end it is counterbored to loosely receive a sleeve 44 which fits upon the shaft, the extreme end of the sleeve 35 being enlarged to form a hub 45, within which is fitted a ball bearing casing 46, the inner member of which is mounted upon the sleeve 44 and abuts against a stop flange thereon. The shifting annulus 42 is held between an annulus 47 secured to the hub 45, as by means of a lateral threaded flange 48, and an annulus 49 secured to the sleeve 44, as by means of a lateral threaded flange 50—a wear plate 51, in annular form, preferably being interposed between the annulus 47 and the annulus 42.

An annular wear plate 52 is fixed upon the shaft 10 back of the annulus 49, and bears against the inner end of a box 53 within which the shaft 10 is journaled. As a means for locking the annulus 52 to the shaft, there is shown a pair of semi-circular plates 54, 55, which fit within a recess in its inner face, and are secured thereto against angular movement by means of studs or dowel pins 56, 57, entering complementary recesses in the annulus. The plates 54, 55, are seated in a circumferential channel in the shaft 10, which channel is interrupted by stop shoulders 58, 59, entering complementary recesses in the plates, and are held against radial displacement by the outer walls of the recess in the plate 52 within which they are seated.

The annulus 42 is provided with a lug 60, fitting loosely within a recess in the arch of the yoke 39, thereby positively holding the annulus against turning movement. A toothed quadrant 61 is secured to the exterior of the casing 12, and co-operates with a spring latch 62 mounted on the hand lever 37 for holding this lever and the parts controlled thereby in adjusted positions.

When the lever 37 is in the position shown in Fig. 1, the fulcrum roller 34 occupies the outer end and deepest portion of the oblique channel in the lever 30; that is to say, it is located at the maximum distance from the pin 31 attaching the lever to the eccentric which it is adapted to attain. The spring 32 is then under a minimum tension, and the governor acts at the lowest speed desired. The shifting of the hand lever 37 to the right from the position shown in Fig. 1 advances the fulcrum roller 34 along the inclined channel in the lever 30 causing it to approach the pivot point 31, thereby increasing the tension of the spring 32 to correspond with the increased centrifugal force at the higher speeds of the governor weights when they are in against the shaft.

The advance of the fulcrum point along

the oblique track also changes the leverage of the spring lever 30, so that the movement of the weights outward at the higher speeds gives an increased spring elongation corresponding with the augmented increase of centrifugal force of the weights from in to out position, at the higher speeds; hence the engine speeds are controlled by movement of the hand lever 37.

- 10 The sleeve 35 is rotatably mounted upon the shaft not only in order that the fulcrum roller may move along the oblique channel in the lever 30, but also to provide for its movement relatively to the shaft incident to 15 the change of position of the eccentric as the governor acts. The pressure exerted by the lever 30 upon the sleeve 35, urging it toward the shaft, is mainly supported by the ball bearing 46, thereby reducing the friction 20 and permitting free angular movement of the sleeve incident to the action of the governor. Ball bearings are not located at the forward end of the sleeve 35, merely because of mechanical difficulties incident to their 25 introduction.

The action produced by the supplemental spring, lever and shiftable fulcrum is illustrated in the diagrammatic Figs. Nos. 8 and 9. In Fig. 8 the position of the eccentric 30 16, supplemental spring 32, lever 30 and fulcrum 34, when the engine is at rest and the adjustment is for low speed, are indicated in solid lines. The positions of these parts when the weights have moved out are indicated in dotted lines. It will be seen that the shifting of the eccentric to the right carries with it the pivot 31 and the end 33 of the spring 32, while the free end of the lever 30 is moved to the left, carrying with it the 40 opposite end of the spring. Thus the spring is stretched from both ends.

In Fig. 9 the positions of these several parts while the engine is at rest, but with the fulcrum 34 shifted to provide for a 45 higher engine speed, are indicated by solid lines; and their positions when the weights are moved out are indicated in dotted lines. It will be seen that as the fulcrum has been moved nearer to the pivot 31 than in Fig. 8, 50 the movement of the free end of the lever to the left, due to the movement of the eccentric, is increased, thereby securing a greater augmentation of spring resistance than when the fulcrum is in the position of 55 Fig. 8, to correspond with the greater augmentation of centrifugal force as the weights move out at the higher speeds than results from their outward movement at lower speeds.

- 60 All of the springs 24, 25 and 32 have a retracting action upon the weights 19, 20. While three springs are preferably used, situations may arise in which the spring 32 will be sufficient to retract the weights, in 65 which case the springs 24, 25, may be dis-

pensed with. Furthermore, the weights may be of any desired number.

Various changes in details of construction may be made without departing from the scope of the invention, and I do not, therefore, limit myself to the specific form in which the invention is illustrated and described.

I claim as my invention—

1. In a device of the character described, 75 in combination, a rotatable shaft, a shiftable eccentric carried by the shaft, a weight pivotally carried by the shaft and movable by centrifugal force, operative connection between the eccentric and weight, means 80 for opposing the centrifugal action of the weight, and means manually operable while the shaft is rotating for varying the action of the opposing means to cause the augmentation thereof as the weights move outward at the same rate as the centrifugal force of the weights is augmented by such outward movement at different engine speeds.

2. In an engine governor, in combination, a rotatable shaft, a shiftable eccentric carried by the shaft, a pair of weights responsive to centrifugal force for shifting the eccentric by their movement, a spring opposing the centrifugal action of the 95 weights, a lever independent of the weights acting on the spring and arranged to be oscillated by the shifting movement of the eccentric.

3. In an engine governor, in combination, 100 a rotatable shaft, a shiftable eccentric carried by the shaft, a pair of weights responsive to centrifugal force for shifting the eccentric by their movement, a spring opposing the centrifugal action of the 105 weights, and means independent of the weights for augmenting the spring tension induced by the outward movement of the weights.

4. In an engine governor, in combination, 110 a rotatable shaft, a pair of weights pivotally carried by the shaft and movable radially with reference thereto, means for opposing the centrifugal action of the weights, and supplemental means connected 115 to a moving part of the governing mechanism other than the weights for augmenting the opposing means as the weights move outward.

5. In an engine governor, in combination, 120 a rotatable shaft, a pair of weights pivotally carried by the shaft and movable radially with reference thereto, means for opposing the centrifugal action of the weights, and supplemental means connected 125 with a moving part of the governing mechanism other than the weights for augmenting the normal action of the opposing means as the weights move outward.

6. In an engine governor, in combina- 130

tion, a rotatable shaft, a pair of weights pivotally carried by the shaft and movable radially with reference thereto, means for opposing the centrifugal action of the 5 weights, supplemental automatic means independent of the weights for augmenting the opposing means as the weights move outward, and manually controlled means for varying the action of the supplemental 10 augmenting means.

7. In an engine governor, in combination, a rotatable shaft, a pair of weights pivotally carried by the shaft and movable radially with reference thereto, means for 15 opposing the centrifugal action of the weights, supplemental means independent of the weights for augmenting the opposing means as the weights move outward, and manually controlled means for varying the 20 action of the augmenting means.

8. In an engine governor, in combination, a rotatable shaft, a pair of radially movable weights pivotally carried by the shaft, means for opposing the outward 25 movement of the weights, supplemental means independent of the weights for augmenting the opposing means as the weights move outward, and manually controlled means for changing the action of the 30 supplemental means.

9. In an engine governor, in combination, a rotatable shaft, a radially movable weight carried by the shaft, a shiftable eccentric mounted directly upon the shaft, 35 connection between the weight and the eccentric, a spring acting on the eccentric in opposition to the outward movement of the weight, a lever pivoted to the eccentric and connected to the spring, and a fulcrum for the lever carried by the shaft.

10. In an engine governor, in combination, a rotatable shaft, a radially movable weight carried by the shaft, a shiftable eccentric carried by the shaft, connection be- 45 tween the weight and the eccentric, a spring acting on the eccentric in opposition to the outward movement of the weight, a lever pivoted to the eccentric and connected to the spring, a fulcrum for the lever carried by the shaft and angularly movable 50 thereon.

11. In an engine governor, in combination, a rotatable shaft, a radially movable weight carried by the shaft, a shiftable eccentric carried by the shaft, connection be- 55 tween the weight and the eccentric, a lever pivotally attached at one end to the eccentric, a fulcrum mounted on the shaft and engaging the lever intermediate of its ends, and a spring reacting between the movable 60 end of the lever and the eccentric.

12. In an engine governor, in combination, a rotatable shaft, a radially movable weight carried by the shaft, a shiftable eccentric

carried by the shaft, connection be- 65 tween the weight and the eccentric, a lever pivotally attached at one end to the eccentric, a fulcrum oscillatably carried by the shaft and engaging the lever intermediate of its ends, and a spring reacting be- 70 tween the movable end of the lever and the eccentric.

13. In an engine governor, in combination, a rotatable shaft, a radially movable weight carried by the shaft, a shiftable eccentric carried by the shaft, connection between the weight and the eccentric, a lever pivotally attached at one end to the eccentric, a fulcrum oscillatably carried by the shaft and engaging the lever intermediate of its ends, 80 a spring reacting between the movable end of the lever and the eccentric, and manually controllable means for moving the fulcrum relatively to the shaft.

14. In an engine governor, in combination, 85 a rotatable shaft, a radially movable weight carried by the shaft, a shiftable eccentric carried by the shaft, connection between the weight and the eccentric, a lever pivotally attached at one end to the eccentric, a ful- 90 crum carried by and axially movable on the shaft and engaging the lever intermediate of its ends, and adapted by such movement to swing the lever on its pivot, and a spring reacting between the movable end of the lever 95 and the eccentric.

15. In an engine governor, in combination, a rotatable shaft, a radially movable weight carried by the shaft, a shiftable eccentric carried by the shaft, connection between the weight and the eccentric, a lever pivotally attached at one end to the eccentric, a fulcrum carried by and axially movable on the shaft and engaging the lever intermediate of its 100 ends and adapted by such movement to 105 swing the lever on its pivot, a spring reacting between the movable end of the lever and the eccentric, and manually controlled means for moving the fulcrum.

16. In an engine governor, in combination, 110 a rotatable shaft, a radially movable weight carried by the shaft, a shiftable eccentric carried by the shaft, connection between the weight and the eccentric, a lever pivotally attached at one end to the eccentric, a ful- 115 crum carried by and axially movable on the shaft and engaging the lever intermediate of its ends, the bearing face of the lever upon the fulcrum being transversely inclined, and a spring reacting between the movable end 120 of the lever and the eccentric.

17. In an engine governor, in combination, a rotatable shaft, a radially movable weight carried by the shaft, a shiftable eccentric carried by the shaft, connection between the weight and the eccentric, a lever pivotally attached at one end to the eccentric, a fulcrum carried by and axially movable on the 125

shaft and engaging the lever intermediate of its ends, the bearing face of the lever upon the fulcrum being transversely inclined, a spring reacting between the movable end of 5 the lever and the eccentric, and manually controllable means for moving the fulcrum.

18. In an engine governor, in combination, a rotatable shaft, a radially movable weight carried by the shaft, a shiftable eccentric 10 carried by the shaft, connection between the weight and the eccentric, a spring acting on the eccentric in opposition to the outward movement of the weight, a lever pivoted to the eccentric and connected to the spring, 15 and a fulcrum for the lever carried by the shaft and being oscillatable and reciprocable thereon, the face of the lever being provided with an oblique track for the fulcrum.

19. In an engine governor, in combination, 20 a rotatable shaft, a radially movable weight carried by the shaft, a shiftable eccentric carried by the shaft, connection between the weight and the eccentric, a spring acting on the eccentric in opposition to the outward 25 movement of the weight, a lever pivoted to the eccentric and connected to the spring, and a fulcrum for the lever carried by the shaft and being oscillatable and reciprocable thereon, the face of the lever being provided 30 with an oblique track for the fulcrum, such track being inclined to a plane intersecting the free end of the lever and passing axially through its pivot.

20. In an engine governor, in combination, 35 a rotatable shaft, an eccentric pivotally carried by the shaft, a radially movable weight pivotally carried by the shaft, connection between the weight and the eccentric, a lever pivoted to the eccentric, a spring urging the 40 free end of the lever toward the shaft, an oscillatable and reciprocable sleeve mounted on the shaft and carrying a fulcrum for the lever, the face of the lever having an oblique slot for engaging the fulcrum, and a hand 45 lever for reciprocating the sleeve.

21. In an engine governor, in combination, a rotatable shaft, an eccentric pivotally carried by the shaft, a radially movable weight pivotally carried by the shaft, connection 50 between the weight and the eccentric, a lever pivoted to the eccentric, a spring urging the free end of the lever toward the shaft, an oscillatable and reciprocable sleeve mounted on the shaft and carrying a fulcrum for the 55 lever, the face of the lever having an oblique slot for engaging the fulcrum and being of greater depth at one end than at the other, and a hand lever for reciprocating the sleeve.

22. In an engine governor, in combination, 60 a rotatable shaft, an eccentric pivotally carried by the shaft, a radially movable weight pivotally carried by the shaft, connection between the weight and the eccentric, a lever pivoted to the eccentric, a spring urging the 65 free end of the lever toward the shaft, an

oscillatable and reciprocable sleeve mounted on the shaft, a roller journaled on the sleeve and forming a fulcrum for the lever, its axis being oblique to the shaft axis, the face of the lever having an oblique slot for engaging 70 the roller, and a hand lever or reciprocating the sleeve.

23. In an engine governor, in combination, a rotatable shaft, an eccentric pivotally carried by the shaft, a radially movable weight pivotally carried by the shaft, connection between the weight and the eccentric, a lever pivoted to the eccentric, a spring urging the free end of the lever toward the shaft, an oscillatable and reciprocable sleeve mounted on the shaft, a roller journaled on the sleeve and forming a fulcrum for the lever, its axis being oblique 75 to the shaft axis, the face of the lever having an oblique slot for engaging the roller, 80 such slot being of greater depth at one end than at the other, and a hand lever for reciprocating the sleeve.

24. In an engine governor, in combination, a rotatable shaft, an eccentric pivotally carried by the shaft, a weight pivotally carried by the shaft and being movable radially, a lever pivoted to the eccentric, a retractile spring attached to the eccentric at the opposite side of its pivot from the 95 pivot of the lever and being attached to the free end of the lever, and a fulcrum for the lever mounted on the shaft.

25. In an engine governor, in combination, a centrifugally acting weight, a spring 100 opposing the centrifugal action, and means for varying the rate of augmentation of the spring resistance due to the outward movement of the weight, whereby the governor may be adapted to maintain constant different rates of engine speeds.

26. In an engine governor, in combination, opposed centrifugal and centripetal acting means, and means for adjusting the centripetal means to cause the governor to 110 maintain constant different rates of engine speeds.

27. In an engine governor, in combination, a rotatable shaft, a weight pivotally carried by the shaft and movable radially 115 with reference thereto, means for opposing the centrifugal action of the weight, such means normally increasing in force as the weight moves outward, and automatic means for varying the rate of such increase of the 120 strength of the opposing means.

28. In an engine governor, in combination, a rotatable shaft, a weight pivotally carried by the shaft and movable radially 125 with reference thereto, means for opposing the centrifugal action of the weight, and supplemental means controlled by the movement of the eccentric for augmenting the normal action of the opposing means.

29. In an engine governor, in combina- 130

tion, a shiftable eccentric, a centrifugal weight for shifting the eccentric, a spring for resisting the centrifugal action of the weight, and means controlled by the movement of the eccentric due to the centrifugal force of the weight for stretching the spring beyond the extent of movement of the eccentric.

30. In an engine governor, in combination, a shiftable eccentric, a centrifugally acting weight for shifting the eccentric, a spring opposing the centrifugal force of the weight, and means controlled by the movement of the eccentric for stretching the

spring to an extent exceeding the movement 15 of the weight.

31. In an engine governor, in combination, a shiftable eccentric, a centrifugal weight for shifting the eccentric, a spring resisting the centrifugal action of the weight, and means controlled by the movement of the eccentric due to the outward movement of the weight for augmenting the rate of increase of spring resistance.
